(57) CLAIM

The ornamental design for a stemless drinkware, as shown and described.

DESCRIPTION

FIG. 1 is a top perspective view of a stemless drinkware; FIG. 2 is a front elevational view thereof, the rear view, right side view, and left side view being identical; FIG. 3 is a top view thereof; FIG. 4 is a bottom view thereof; and, FIG. 5 is a cross-sectional view taken along line 5-5 of FIG. 2.

The broken lines in the drawings illustrate portions of the stemless drinkware that form no part of the claimed design.
